(57) CLAIM

The ornamental design for housing cover, as shown and described.

DESCRIPTION

This application contains at least one drawing executed in color. Copies of this patent or patent application publication with color drawing(s) will be provided by the Office upon request and payment of the necessary fee.

The sole FIGURE is a front plan view of the housing cover showing my new design.

The design consists of the appearance as shown in a flat plane with no depth or contour.
